UNITED STATES PATENT OFFICE.

EMIL CLAVIEZ, OF LEIPSIC, GERMANY.

SHUTTLE-CHANGING MECHANISM FOR LOOMS.

SPECIFICATION forming part of Letters Patent No. 633,952, dated September 26, 1899.

Application filed June 24, 1897. Serial No. 642,078. (No model.)

To all whom it may concern:

Be it known that I, EMIL CLAVIEZ, a citizen of the German Empire, residing at Leipsic, Germany, have invented certain new and useful Improvements in Shuttle-Changing Mechanism for Looms, of which the following is a specification.

The invention relates to shuttle-changing mechanism for looms in which a vertical row of separate shuttles is arranged in front of the lay and is supported on a fixed table so that the bottom shuttle may be called into action whenever a change of color is to be made. When the shuttles are to be changed, the lowermost of the vertical row of shuttles is pushed along the table into the advancing lay after a previous shuttle has been removed backward from the lay. The mechanisms for removing the old and inserting the new shuttle are set in action either by an electromagnet or by purely mechanical means.

In the accompanying drawings, Figure 1 is a side elevation of a loom, showing the shuttle-changing mechanism. Fig. 2 is a rear elevation of part of the loom, showing said changing mechanism from the left of Fig. 1. Fig. 3 is a plan view of the said mechanism. Figs. 4 to 7 are diagrammatic views illustrating the manner of ejecting the old and inserting the new shuttle. Figs. 8 to 10 show the main working parts in various working positions. Figs. 11 and 12 show an electromagnet for determining the time when the change of shuttle is to occur.

Similar letters of reference indicate corresponding parts.

The loom may be of any preferred construction, consisting of the frame, lay, heddles, &c., which are not necessary to be herein particularly illustrated or described, but which are sufficiently illustrated and described so as to enable persons skilled in the art of weaving to adapt the present improvements thereto.

The working shaft of the loom carries a cam E, which through the medium of a link G, which has an antifriction-roller arranged in the cam-groove of the cam E, oscillates a lever H, which is fulcrumed at its lower end at L at a suitable point on the frame of the machine, and said lever H has pivoted to its upper end a pawl K, the tooth of which is adapted to engage with a projection v, extending in the

opposite direction from a latch F, which is pivoted to the upper end of said lever H, above the pivotal point of the pawl K. The upper end of pawl K is adapted to engage the lower end h of an armature m of an electromagnet M, which is arranged on the frame of the loom. This engagement of the pawl K with the lower end h of said armature can only be effected when the same is drawn toward the magnet. The armature is forced out by means of a lever H⁴, pivoted at a suitable point to the frame of the machine and being under the tension of a spring, said lever being operated by means of a cord o, guided over a suitable pulley on the frame and attached at its lower end to a lever H², pivoted at n to the lower portion of the frame of the machine. This lever H² has a pin-and-slot connection d, as shown clearly in Figs. 1 and 9, with the elbow-lever H³ of a second lever H', which is pivoted at its lower end at l to the frame of the machine. S is an upright rod which carries at its upper end a plate W, to be herein-after particularly described. The said lever H' is provided with a pin a, over which the hook end x of the latch F, which is pivoted to the lever H, is adapted to engage, while on the other hand the lever H' is provided with a pawl k', the hook end of which is adapted to engage a projection R on the lay. (See Figs. 9 and 10.)

Arranged at the upper forward portion of the frame of the loom is a fixed table T, upon which slides a push-wall w, which is operated by the upper end of said oscillating lever H'. The shuttle holding or collecting box B is arranged in upright position above the table T and contains a vertical row or tier of shuttles, which are to be transferred one by one to the lay. Arranged parallel with the push-wall w is the aforesaid front wall W, which is carried at the upper end of the vertically-movable rod S, while arranged parallel with the front wall W is a rear wall A, which is pivoted at i to a suitable point of the lay.

The main working parts of the shuttle-changing mechanism having been briefly outlined, the operation of the same will now be particularly described.

The changing of the shuttles takes place through the medium of the three movable sides or walls—to wit, A, W, and w. Of

these the shuttle-box walls on the change side are formed by the front wall W and the rear wall A, while the wall w is movable forward and backward toward the lay on the fixed table T, arranged in front thereof under the shuttle - collecting box. (See particularly Figs. 4 to 7.) By the term "change side" in the present invention is intended that side on which the improved shuttle - changing mechanism itself is located, and the front wall W and the rear wall A are in particular meant thereby for the reason that the changing of the shuttles is brought about through the influence of the three movable walls, one of which, w, moves under the shuttle-box B. When the change is to be effected, the inner end of the rear wall A is moved into the box, Figs. 3 and 4. Consequently the shuttle coming from the other side slides under the inclined wall A and is conveyed out of the lay onto a suitable incline, which delivers it into a collecting-receptacle at the disposal of the weaver. On the succeeding forward movement of the lay the front wall W rises, and push-wall w by the movement toward the lay pushes the lower shuttle of the vertical row of shuttles from the table T into the lay, Figs. 1 and 5. The inserted shuttle then forces the rear wall A into its original position parallel with the walls W and w. The walls W and w follow the shuttle backward and form the front wall of the shuttle-box until the shuttle movement, Fig. 6, takes place. The wall w then returns to the table T, whereupon the main-shuttle front wall W returns backward into its former position. (Shown in Fig. 4.) If the wall w in its return movement moves far enough to the right, a new shuttle will fall downward from the receptacle B, Fig. 7. As the insertion of a new shuttle in the lay now immediately takes place, it is possible to change both shuttles with one change. These movements of the walls A, W, and w are carried out through the medium of the instrumentalities above described, as follows: When it is desired to change the shuttles, a current from a suitable source of electricity and in connection with such a pattern mechanism as is fully shown and described in my Patent No. 572,245, dated December 1, 1896, is caused to pass through the coils of the electromagnet M, so that its armature m is drawn toward the same to the left, as shown in Figs. 2 and 11. The projection g at the upper end of the armature m is thus brought into the path of a trip-lever F', which is pivoted to the lay at a suitable point, as s, above the electromagnet and which is at this time moving backward with the lay, which trip-lever, consequently, encountering the said projection g, rocks on its pivots and through the medium of its projection s' raises an arm t', (see Fig. 12,) so as to operate a latch N, which is also pivoted to the lay near the free end of the rear wall A. This latch N is, by means of a spring n', forced upwardly, so that its tooth u is caused to engage with the free end of said

rear wall A, when the same has been forced into position parallel with the front wall W by the insertion of a new shuttle. By the pushing up of the arm t' the latch N is released from the movable end of the hinged rear wall A, so that the same, under the action of its spring k, is moved on its pivot i into oblique position relatively to the shuttle-box, 75 so that the shuttle coming from the other side will slide along the back of the said wall and be thus removed from the lay. On the subsequent forward movement of the lay the pawl K of the lever H encounters the lower projection h on the armature m and is then drawn to the left, Fig. 8, so that the said pawl K is thereby held back and releases the latch F, which was previously engaged by the tooth of the pawl. The latch F now drops and engages by its outer hook end x the pin a on the lever H' and draws this lever onto the lay on the return of the said lever H. The lever H is thereby caused to push the wall w along the table T, whereby the lowermost shuttle 90 is forced from said table into the lay. Just before this movement, however, the shuttle-wall W must be raised, and to this end the lever H', by means of its elbow projection H², during its movement to the rear, raises the lever H², Figs. 1 and 9, whereby the upright rod S is moved upwardly so as to push up the front wall W. In order that the push-wall w may remain on the lay during the pushing off of the shuttle and may form the front wall of the shuttle-box, the pawl K, carried by the lever H', is caused to engage with the projection R on the lay, so that the lever H' and the wall w must move together to the rear with the lay. The extent to which the said lever H' is carried backward by the lay is limited by a link Z, pivoted at its upper end to the forwardly-projecting portion of the pawl K' and at its lower end having a slotted frame or head c, which is guided on 100 an adjustable bolt y, arranged on the frame of the loom. By this means at the proper moment the hook of the said pawl K' is lifted and disengaged from the projection R, whereupon a tension-spring f, or its equivalent, 115 draws the lever H' again to the front, while the levers H²H³ and the rod S lower the front wall W. The lifting of the latch F takes place when the pin a on the lever H' encounters the bulge or projection q on the latch F, 120 the latter being raised so far that the tooth of the pawl K under the action of its spring f' can again engage the projection v of said latch and hold the same in raised position until it is again released by said pawl.

Having thus described my invention, what I claim is—

1. In a shuttle - changing mechanism for looms, the combination, with a collecting-box, a table below said box, a push-wall guided along said table, a horizontally-movable rear wall on the lay, and a vertically-movable front wall, of means for moving the rear wall and push-wall away from the collecting-box, along

said table, so as to transfer the lowermost shuttle from the said box to the lay, and means for raising and lowering the front wall, said front wall being lowered relatively to the collecting-box when the push-wall has been returned to forward position, substantially as set forth.

2. In a shuttle-changing mechanism for looms, the combination with a collecting-box, a table below said collecting-box, a rear shuttle-box wall, pivoted to the lay of the loom so as to be horizontally movable, a spring tending to hold the said pivoted wall in oblique

position relatively to the lay, and means for holding the said pivoted rear wall retracted, ¹⁵ against the force of said spring, of a vertically-movable front wall, means for moving the front wall, a push-wall guided on the said table, below the collecting-box, and means for moving said push-wall, substantially as set ²⁰ forth.

EMIL CLAVIEZ.
